UNITED STATES PATENT OFFICE

FRANK D. WILDER, OF WESTPORT, CONNECTICUT

STREET INDICATOR

Application filed June 27, 1930. Serial No. 464,382.

My invention relates to a street and station indicator particularly adapted for railway and street car lines.

It is an object of the invention to provide an indicator which will successively display the name of the station or street at which the car or train will next stop, for the convenience of the passengers.

A further object of the invention is to provide a novel mechanism for turning the rollers on which the web carrying the names of the streets or stations is wound and means for

reversing the rotation of the rollers so that the web may be moved in either direction.

15 A still further object of the invention is to provide means for adjusting the web so that if the names of the stations or streets get out of alignment with the window through which they are displayed they may be readily re-

20 aligned with the window again.

Another object of the invention is to provide a device of the above mentioned character which is simple and durable in construction, reliable and efficient in operation and inexpensive to manufacture.

Other objects and advantages of the invention will be apparent during the course of the following description.

In the accompanying drawings, forming a part of this specification and in which like numerals are employed to designate like parts throughout the same,

Fig. 1 is a front elevation view of the indicator,

35 Fig. 2 is a longitudinal sectional view of the same taken on lines 2—2 of Fig. 1,

Fig. 3 is a similar view taken on lines 3—3 of Fig. 1,

40 Fig. 4 is a horizontal sectional view taken on lines 4—4 of Fig. 1,

Fig. 5 is a vertical section taken on lines 5—5 of Fig. 2,

45 Fig. 6 is a horizontal section taken on lines 6—6 of Fig. 1,

Fig. 7 is a longitudinal section taken on lines 7—7 of Fig. 5, and

Fig. 8 is a longitudinal section taken on lines 8—8 of Fig. 5.

50 In the drawings, wherein for the purpose of illustration I have shown a preferred em-

bodiment of my invention, the numeral 5 denotes generally a metal casing having a back wall 6, side walls 7, end walls 8 and a front wall 9 having one of its longitudinal edges hingedly connected to one of the side walls, 55 as at 10, so as to swing open and permit ready access to be had to the interior of the casing.

The casing may be mounted in the train or street car by means of the brackets 11 attached to the back of the casing and projecting beyond the sides thereof adjacent the upper end.

5 A pair of rollers 12 and 13 are arranged respectively in the upper and lower ends of the casing, the axle shafts 14 and 15 of the rollers being journaled in the bearings 16 in the side walls 7 of the casing. A flexible web 17 has its ends secured to the rollers 12 and 13 by the clamping strips 18 which are secured in the grooves 19 extending longitudinally of the rollers. The web is trained over the guide rods 20 disposed between the rollers in horizontal spaced relation adjacent the front wall of the casing, the ends of the rods being journaled in bearings 21 attached to the side walls of the casing. The guide rods hold the web in close relation to the window 22 mounted in the opening 23 formed in the front wall 9, so that the names of the streets or stations inscribed upon the web, at spaced intervals, may be readily seen through the window, as they are brought into alignment with the window as the rollers are turned.

70 75 80 85 The mechanism for turning the rollers the required distance so as to bring the names on the web successively in alignment with the window consists of a toothed wheel 24 mounted on one end of the axle 15 of the lower roller 13, the wheel having a collar 25 through which a set screw 26 extends fixedly connecting the wheel to the axle. Loosely mounted on the axle next to the wheel 24 is a sector gear 27, the teeth of which are adapted to mesh with the rack bar 28 mounted to reciprocate in the guide block 29 attached to the side wall of the casing by rivets 30. One end of the rack bar extends through the lower end wall of the casing having a handle 31 attached thereto, whereby the rack bar may be

90 95 100

reciprocated to impart an oscillating motion to the sector gear. One portion of the sector gear extends beyond the periphery of the wheel 24 and a reversible pawl 32 is pivoted 5 to the side thereof next to the wheel 24, as at 33. The pawl is adapted to oscillate so as to bring the teeth of the pawl alternately into engagement with the teeth of the wheel 24 establishing connection between the 10 sector gear 27 and wheel 24, thereby rotating the roller 13 in one direction upon completion of a full stroke of the rack bar, the direction of rotation of the roller depending upon which tooth of the pawl is engaged 15 with the wheel 24. The pawl is releasably held in its alternate positions by the leaf spring 34 attached to the edge of the sector gear, as at 35, the free end of the spring engaging the beveled faces 36 of the pawl. The 20 pawl is oscillated by the lug 37 projecting from the rod 38, journaled in the sector gear, which extends through the arcuate slot 39 formed in the side wall of the casing and a thumb wheel 40 is mounted on the outer end of the rod for turning the same. Upon 25 turning the rod 38 the lug 37 engages the notch 41 formed in the pawl intermediate the teeth thereof, oscillating the pawl to move the teeth thereof alternately into engagement 30 with the teeth of the wheel 24, to change the direction of rotation of the roller 13.

Mounted on the axle 15 at the opposite end of the roller 13 is a ratchet wheel 42 fixedly connected to the axle, and loosely mounted on the axle next to the ratchet wheel is a relatively large belt pulley 43, having a pawl 44 pivoted, as at 45, to the side of the pulley, which is held in engagement with the ratchet 35 wheel by the leaf spring 46 attached to the side of the pulley, as at 47. The axle 14 of the roller 12 has a relatively small belt pulley 48 loosely mounted thereon adjacent one end of the roller in vertical alignment with the belt pulley 43 and an endless belt 49 is trained 40 over the pulleys establishing connection between the two rollers. Disposed between the pulley 48 and end of the roller 12 is a friction drive disk 50 which is attached to the end of the roller. The disk 50 is held in 45 frictional contact with the pulley 48, by means of the coil spring 51 mounted on the opposite end of the axle 14, which is seated in the enlarged end 52 of the roller bore and exerts a longitudinal pressure on the roller. 50 The end of the axle 15 adjacent the pulley 43 extends beyond the side wall of the casing and has a thumb wheel 53 attached thereto, whereby the roller 13 may be readily turned 55 to quickly align the names on the web with the window.

In operation, it will be seen that upon reciprocation of the rack bar 28, the wheel 24 is rotated, turning the roller 13, the direction of rotation of the roller depending 60 on which tooth of the reversible pawl 32

is engaged with the teeth of the wheel 24. When the roller is rotated in the direction to wind the web 17 thereon, the pulley 43 remains stationary, as the pawl 44 rides over the teeth of the ratchet wheel. When the roller is rotated in the reverse direction the pawl 44 engages the teeth of the ratchet wheel 42, causing the pulley 43 to turn therewith and the power of the pulley 43 is transmitted to the pulley 48 by the belt 49 and the pulley 48 turns the roller 12 by reason of its frictional engagement with the friction disk 50, winding the web thereon. Upon each full stroke of the rack bar the web is moved a pre-determined distance so as to bring the names inscribed on the web successively in alignment with the window 22 through which they are displayed. The direction of movement of the web is readily reversed by turning the thumb wheel 40, which trips the pawl 32 reversing the rotation of the roller 13. Should the names on the web get out of alignment with the window, the web may be readily adjusted by turning the thumb wheel 53, which rotates the roller 13. While the rack bar as shown is manually actuated, it is apparent that the same may be actuated by an electric motor if so desired.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:

1. In an indicator of the class described, a pair of rollers mounted for rotation, a web having its ends connected to said rollers, a toothed wheel fixedly mounted on the shaft of one of said rollers, a sector gear loosely mounted on the shaft of said roller, a reversible pawl pivotally connected to the side of said sector gear adapted to establish connection between said sector gear and toothed wheel, a casing for the rollers having an arcuate slot, a pin pivotally carried by the sector gear and projecting through the slot, the outer end of the pin being provided with an operating knob, cooperating means between the pin and the pawl for reversing the pawl, and a rack bar suspended from the sector gear for actuating the latter, said slot and pin limiting the movement of the sector gear whereby to prevent displacement of the rack bar from the casing.

2. In an indicator of the class described a casing having an arcuate slot, a pair of rollers mounted for rotation in the casing, a web having its ends connected to said rollers, a toothed wheel fixedly mounted on the shaft of one of said rollers, a sector gear loosely mounted on the shaft of said roller,

a reversible pawl pivotally connected to the side of said sector gear adapted to establish connection between said sector gear and toothed wheel, a pin pivotally carried by the 5 sector gear projecting through the slot of the casing and having an operating knob on its outer end, cooperating means between the pin and the pawl for reversing the pawl, a reciprocating rack bar depending through 10 an opening in the casing and adapted to mesh with said sector gear to actuate the same, said pin and slot limiting the movement of the sector gear whereby to prevent displacement of the rack bar, a pulley loosely mounted on the 15 shafts of said rollers, an endless belt trained over said pulleys, and clutches for establishing connection between said pulleys and rollers.

In testimony whereof I affix my signature.

FRANK D. WILDER.
